UNITED STATES PATENT OFFICE.

CHARLES T. SEGAR, OF UTICA, NEW YORK.

SPRING CURTAIN-ROLLER.

SPECIFICATION forming part of Letters Patent No. 240,191, dated April 12, 1881.
Application filed February 19, 1880.

To all whom it may concern:

Be it known that I, CHARLES T. SEGAR, of Utica, in the county of Oneida and State of New York, have invented a new and valuable Improvement in Spring Curtain-Fixtures; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a longitudinal section of my improved fixture, and Figs. 2 and 3 are details.

This invention has relation to spring curtain-rollers; and it consists in the construction and novel arrangement of parts, as hereinafter shown, described, and particularly pointed out in the claim.

The object of this invention is to provide a spring-fixture for curtain-rollers which will occupy but little transverse space at the end of the roller, and will at the same time be effective in its operation and simple in its construction.

In the accompanying drawings, the letter A designates an ordinary solid curtain-roller, having at one end a plate, a, in which there is a central square hole, b.

B indicates the disk-shaped box or spring-case, consisting of a circular rim, c, and a centrally-perforated outer wall portion or plate, d, which is extended on the side next the window, as indicated at e, and provided with a fastening-flange, f, through which screws can be passed to attach the fixture to the window-frame. This box has very little transverse depth, only sufficient being required for the reception of the coiled ribbon-spring g, the

spring disk-guard h, and the spindle-flange which plays between the disk-guard and the face or cover k of the box, which is next the roller end, as shown in the drawings. One end of the spring g is attached to the rim of the box and the other or inner end to the spindle s, which is centrally located in the box and passes transversely through it, having narrow journals l l', which bear in the circular central openings m m of the side wall and face of the box. At one end of the spindle, projecting outward beyond its journal, is a squared lug, n, which is designed to engage with the hole b

of the end plate, a, of the roller. Next to this journal l is the disk-shaped flange p of the spindle, the margin of which is notched at opposite points, as indicated at q, these notches being slightly beveled at one side, near the margin, so that the end of the pawl z which is pivoted to the face or cover k of the box, and which is also beveled on one side, will readily pass the notches when the curtain is pulled down, and will engage one of them when the curtain is brought into the required position. The end of the pawl z is also somewhat beveled on its point portion, as indicated at i, so that under the rapid action of the spring in raising the curtain it will pass over the notches in the opposite direction, falling into engagement with one of them when the curtain is stopped.

Between the flange p of the spindle and the outer journal, l', is the core or heel portion v, to which the inner end of the spring is secured, and on which it is wound when the curtain is actuated by pulling it down. The journal l' is separated from the core v, which is of larger diameter, by a shoulder, u, which keeps the outer wall of the box from pressing on the spring and impeding its action.

h represents a large inner disk, having a central opening of sufficient size to be passed on the core v, this being done before the spring g is attached thereto, so that the disk will form a guard for the spring and keep it from interfering with the action of the pawl and the notched flange of the spindle.

I am aware that a short shaft mounted in a case carried on one of the brackets, and the projecting end of which short shaft engages with and supports one end of the curtain-roller, and imparts thereto the effect of the spring, has been used in combination with a pawl mounted on the fixed portion and engaging a notch in the short shaft, as may be seen in Patent No. 195,962, of October 9, 1877, and I desire to make no claim herein for said construction, broadly, but wish to limit myself to the construction herein shown and described, and hereinafter particularly pointed out in the claim.

Having described this invention, what I claim, and desire to secure by Letters Patent, is—

In a spring roller-fixture for curtains, the combination of the disk-shaped box B, having the

face-cover *k*, the spindle *s*, having journals *l l'*,
squared projection *n*, core *v*, and notched disk-
shaped flange *p*, the ribbon-spring *g*, coiled with-
in the box *B*, between the face *d* and disk-guard
5 *h*, and attached to the box and core, and the
bevel-end pawl *z*, pivoted to the face-cover,
substantially as and for the purposes set forth.

In testimony that I claim the above I have
hereunto subscribed my name in the presence
of two witnesses.

CHARLES T. SEGAR.
